CRANKPIN TRUING DEVICE

Robert W. Barker, Ardmore, Pa.

Application July 16, 1935, Serial No. 31,565

8 Claims. (Cl. 82—4)

My invention relates to a new and useful crank pin truing device and is particularly adapted for truing the crank pins on relatively large crank shafts of large engines without the necessity of 5 dismantling such crank shafts, thus eliminating the great expense in time and labor which would be incurred in the dismantling of such crank shafts, my novel truing device being of a portable character and capable of application directly 10 to the crank shaft through any conventional opening in a wall of the crank case.

My invention further relates to a crank pin truing device in which the crank pin engaging member is offset with respect to the supporting 15 member of the device in order to facilitate the engagement of the crank pin truing element with the crank pin of the crank shaft while the supporting element of the truing device is secured to the edge of an opening in a wall of the crank 20 case.

My invention still further relates to a truing device of this character which may be operated manually, or which may be power driven at will, and in which means are provided for effecting 25 accurate adjustment of the cutting knife with respect to the crank pin.

My invention still further relates to a truing device in which the annulus carrying the cutting element is formed of one piece, with an opening 30 therein permitting the insertion of the crank pin to be trued and with means for effecting continuous driving of said annulus as distinguished from a truing device in which the knife carrying annulus is made of two parts which are assembled 35 for the insertion of the crank pin and subsequently assembled about said crank pin.

My invention still further relates to a truing device comprising means for reciprocating the cutter with respect to the work and means for 40 adjusting the driving mechanism of said cutter to compensate for wear.

Other features of novelty and advantage will 45 be more clearly understood from the following specification and the accompanying drawings in which:

Fig. 1 represents a view in elevation of a crank pin truing device embodying my invention, part of the crank pin and the crank case wall to which the device is applied being shown in dotted lines.

Fig. 2 represents a section on line 2—2 of Fig. 1.

Fig. 3 represents a front elevation of Fig. 1.

Fig. 4 represents a fragmentary end view of the right hand end of Fig. 1, showing details of the driving mechanism.

Fig. 5 is an enlarged section on line 5—5 of Fig. 2.

Fig. 6 represents, on an enlarged scale, a view in side elevation of the hand operated driving mechanism shown at the left hand end of Fig. 1. 5

Fig. 7 represents, on an enlarged scale, a fragmentary view in side elevation of the cutter and the mounting thereof.

Fig. 8 represents a section on line 8—8 of Fig. 7.

Fig. 9 represents, on an enlarged scale, a section on line 9—9 of Fig. 3 showing details of the driving mechanism.

Fig. 10 represents a detailed section of the worm drive adjusting mechanism.

Fig. 11 represents a perspective view of a truing 15 device embodying my invention.

Referring to the drawings in which like reference characters designate like parts and more particularly to Fig. 11, 1 designates a crank shaft and 2 designates the crank pin, both shown in 20 dotted lines, in a position to be trued by a truing device embodying my invention. The truing device consists generally of the frame 3 on which is mounted the truing head 4, the screw shaft 6 on which the truing head 4 reciprocates, and the 25 driving mechanism which will be described in more detail in connection with the other figures of the drawings. In order to apply the truing device to the crank pin to be trued, in the manner illustrated in Figs. 2, 3, and 11, a plate is removed 30 from the side wall of the crank case 9 and the frame 3 of the truing device is suitably secured in position on the edge of the crank case with the truing head 4 projecting into the crank case and engaging the crank pin 2. In order to facilitate 35 engagement of the head 4 with the crank pin 2, the head 4 is offset from the frame 3 as best seen in Figs. 2 and 11. The truing head 4 is made of two sections 10 and 12 suitably secured together by the bolts 13 and is carried by the housing 14 40 which slidably engages the frame 3 as at 16. The housing 14 is provided with the threaded nut 18 which engages the threaded shaft or screw 6, so that, when the screw 6 is turned, the truing head 4 will reciprocate along the frame 3. In 45 order to permit insertion of the crank 2 into the truing head 4, the truing head is formed of a circumference less than a circle with the segment 20 (shown detached in Fig. 11) adapted to be clamped in position by the bolts 19 to complete the 50 circumferential bearing after the crank pin 2 is in position within the truing head 4, as best seen in Fig. 2.

Carried by the truing head 4 is the gear ring 24, which carries the cutter 25 suitably clamped 55

in position by the bolt 26 and plate 27. The gear ring 24 is provided with a rib 29 which engages a corresponding groove 30 in the truing head section 10 and with the annular gear 32 which seats 5 in a groove 34 common to the sections 10 and 12. It will be noted that the gear ring 24 is of a circumference less than a complete circle with an opening formed therein large enough to permit insertion of the crank pin 2 to be trued. In order to achieve continuous driving of the gear ring 10 24, despite its discontinuous or incomplete circumference, I provide the worms 38 and 40, which are disposed at an angle to each other, said angle being big enough to intercept a segment of the 15 ring larger than the open segment thereof, so that, the gear 32 of the ring is at all times in mesh with at least one of the worms 38 or 40. In other words, while the open segment of the cutter ring 24 is passing either of the worms 38 or 20 40, the other of the worms is in engagement with the gear 32, thus insuring continuous drive of the ring 24. While I have shown two angularly disposed worms for driving the gear ring 24, it is to be understood that a chain drive can be used, if 25 desired, whereby a portion of the drive chain is at all times in mesh with a portion of the gear 32 on the ring 24.

In order to provide for nice adjustment of the cutter with respect to the work, I have provided 30 the construction best seen in Figs. 7 and 8, from which it will be seen that the cutter 25 is mounted on the block 41 which in turn is secured to the gear ring 24 by the bolt 42 which is adjustable in the slot 42x. Beneath the block 41 is positioned 35 a wedge 44 movable in the chamber 45 and engaged at its opposite ends by the bolts 46, so that, by turning the bolts 46 the wedge 44 will be moved to the right or to the left of Fig. 8, thus raising or lowering the block 41 and hence the cutter 25. 40 This is to afford particularly accurate adjustment in addition to and independently of the ordinary adjustment obtainable by raising or lowering the cutter 25 with respect to its support.

The driving mechanism is as follows; a pulley 45 50 is mounted on the stub shaft 51 which by means of a train of gears (see Fig. 4) transmits power to and rotates the shafts 55 and 58. The shaft 55 carries the gear 60 which meshes with the gear 61 on the shaft 62 which carries and 50 rotates the worm 40. The shaft 62 also carries the beveled gear 64 which meshes with the beveled gear 65 on the shaft 68 which in turn carries the worm 38, so that, by driving the pulley 50 55 and actuating the shaft 55, the shafts 62 and 68 will be actuated to drive the worms 38 and 40. If it is desired to turn the machine by hand a crank handle 70, may be used in lieu of the power driven pulley 50.

The actuation of the shaft 58 transmits power 60 to the screw shaft 6 through the worm 75 which engages the gear 76 on the shaft 77 inclosed in the casing 78. The shaft 77 carries the beveled gears 79 and 80, which in turn are adapted to mesh with the beveled gear 90 on the screw shaft 65 6. The manipulation of the gears 79 and 80 with respect to the beveled gear 90 permits the attainment of a neutral position in which the screw shaft 6 is unaffected by the drive mechanism and also serves to effect reversing of the direction of 70 turning of the screw shaft 6. Thus, if the gear 90 is in engagement with the gear 79, the screw shaft 6 will turn in one direction and the truing head 4 will move in the corresponding direction with respect to the frame 3, and vice versa, if the 75 gear 90 is in mesh with the gear 78. Similarly if

neither of the gears 79 or 80 engages the gear 90, the device is in "neutral" position. In order to determine the engagement of the gear 90 with either of the gears 78 or 79, I turn the knob 94 to turn the pinion 95 which engages with the rack 5 96 on the shaft 97 to move the shaft 97 laterally in its bearings 98. This moves the finger 99 engaging the slot 100 in the shaft 77, intermediate the gears 78 and 79, thus moving the shaft 77 laterally to bring either of the gears 78 or 79 into 10 mesh with the gear 90, or to a position in which neither of the gears 78 or 79 is in engagement with the gear 90. In order to provide means for locking the parts in any one of the three possible positions, I have provided the spring pressed pin 15 104, which is adapted to engage any one of the notches 105, it being understood that one of the notches corresponds to a neutral position of the screw shaft 6, the second of the notches in the position in which the screw shaft 6 turns in a 20 clockwise direction, and the third of said notches corresponds to the position in which the screw shaft turns in counter-clockwise direction.

In Fig. 6, I have shown an arrangement for manual driving of the screw shaft 6 which consists in the crank handle 110 which turns the beveled gear 111, which engages the beveled gear 112 on the screw shaft 6. In order to enable me to position the handle 110 at either side of the screw shaft 6, I provide an auxiliary beveled gear 30 113 which also meshes with the gear 112 and which can be engaged by the handle 110, if so desired.

In Fig. 10 I have shown details of the mounting 35 of the shaft 68 to permit adjustment of the worm 38 to take up the play that may develop due to uneven wear of the worms 38 and 40. According to this construction I provide the tapered bearing 100 against which abuts the nut 101 engaging a correspondingly threaded portion 102. When it 40 is desired to adjust the worm 38, it is merely necessary to loosen the nut 101 and pull out the tapered bearing 100 thus releasing the gear 65 from engagement with the gear 64 and permitting the turning of the shaft 68 to bring an unworn portion 45 of the thread of the worm into contact with the gear 34 on the ring 24, whereupon the tapered sleeve bearing 100 is again wedged onto the shaft 68 and the nut 101 is tightened.

While I have shown and described my crank pin 50 60 truing device as applied to the truing of the crank shaft of an engine by removal of a portion of the crank case thereof, and by mounting of the truing device on the edge of the crank case, it is to be understood that my truing device is equally applicable for the truing of any large shafts such as line shafts in factories, the propeller shafts in steam ships, etc.

It is to be noted that by mounting the frame 3 65 of the truing device to the side wall of the crank case I am better enabled accurately to center the truing device, since the crank case is built solid in a heavy foundation and is accurately aligned as distinguished from the mounting of the truing device on a part of the crank shaft to be trued, due to the fact that the crank shaft part to which the truing device is connected may not, itself, be true due to displacement, or wear and tear. In other words, I provide means for securing the truing device to an external, properly aligned, or 70 properly centered, support, which is independent of the crank shaft to be turned or trued, which is an important feature in arriving at satisfactory and accurate results.

It is also to be noted that the particular manner 75

in which the truing-head is offset with regard to the frame thereof, namely, to both the vertical and horizontal planes of said frame, enables the truing-head to be inserted through relatively small openings, or through limited spaces, for complete access to the part of the shaft to be trued. Further, the provision of a gear-ring, which is bigger than one-half but less than a complete circle, gives the effect of a complete or circular gear-ring without the necessity of the mechanic actually entering the space where the crank shaft is and building a segmental, or sectional, gear-ring about the shaft, as has been the practice in the prior art, as it is represented in the Polderman Patent No. 1,833,589.

Having thus described my invention, what I claim as new and desire to secure by Letters Patent is;

1. A crank pin truing device comprising a frame adapted to be secured to the crank case of the engine, a head reciprocable on said frame, and an arcuately movable cutter carried by said head, said head being offset at an angle with respect to both the vertical and horizontal planes of said frame.

2. A crank pin truing device comprising a frame adapted to be secured to the crank case of the engine, a head reciprocable on said frame, and a cutter carried by said head, said head constituting an arc larger than half of, but less than a complete circle.

3. A truing device for truing the crank pins of large crank shafts, without dismantling the latter, comprising a frame adapted to be secured to the edge of the crank case of the engine, an arcuate element revolvably mounted in offset position with respect to both the vertical and horizontal planes of said frame and having an opening for admitting the crank pin to be trued, a cutter carried by said arcuate element, and angularly dis-

posed driving mechanisms, at least one of which is at all times in contact with said arcuate element for continuously driving the latter.

4. A truing device for truing the crank pins of large crank shafts without dismantling the latter comprising a frame adapted to be secured to the edge of the crank case of the engine, an integral arcuate element revolvably mounted in offset position with respect to both the vertical and horizontal planes of said frame, and having an opening therein adapted to receive the crank pin to be trued, a cutter carried by said arcuate element, and means for continuously driving said arcuate element.

5. A crank pin truing device comprising a frame, a head reciprocable on said frame, and an arcuately movable cutter carried by said head, said head being offset at an angle with respect to both the vertical and horizontal planes of said frame.

6. A crank pin truing device comprising a frame, a head reciprocable on said frame, and a cutter carried by said head, said head constituting an arc larger than half of, but less than a complete circle.

7. A shaft truing device comprising a frame, a head reciprocable on said frame, a gear ring carried by said head, and a cutter carried by said gear ring, said gear ring constituting an arc larger than one-half of but less than a complete circle.

8. A crank pin truing device comprising, a frame adapted to be secured to a support in proximity to the crank pin to be trued, a head reciprocable on said frame, and an arcuately movable cutter carried by said head, said head being offset at an angle with respect to both the vertical and horizontal planes of said frame.

ROBERT W. BARKER. 40
